CLAIM

The ornamental design for the jewelry chain, as shown and described.

DESCRIPTION

FIG. 1 is a perspective view of jewelry chain showing my new design, it being understood that the broken lines indicate that the chain continues uniformly for the distance shown. The broken line showing of clasps are for illustrative purposes only and form no part of the claimed design;

FIG. 2 is a perspective view;

FIG. 3 is a top plan view;

FIG. 4 is a bottom plan view;

FIG. 5 is a cross sectional view taken along the lines 5—5 of FIG. 3; and,

FIG. 6 is a side elevational view.
